Primary Examiner — David G Muller*Assistant Examiner* — Nathan M Johnston*(74) Attorney, Agent, or Firm* — Patterson Thuente
Pedersen, P.A.(57) **CLAIM**

I claim the ornamental design for rod keeper, as shown and described.

DESCRIPTION

FIG. 1 is a top perspective view of a rod keeper showing my new design.

FIG. 2 is a bottom perspective view thereof.

FIG. 3 is a left side elevation view thereof.

FIG. 4 is a right side elevation view thereof.

FIG. 5 is a front elevation view thereof.

FIG. 6 is a rear elevation view thereof.

FIG. 7 is a top plan view thereof; and,

FIG. 8 is a bottom plan view thereof.

Subject matter depicted in broken lines in the Figures forms no part of the claimed design.

1 Claim, 8 Drawing Sheets---
